UNITED STATES PATENT OFFICE.

JAMES J. MELVILLE, OF NORTHWICH, ENGLAND.

APPARATUS FOR TREATING SUBSTANCES WITH GASES.

SPECIFICATION forming part of Letters Patent No. 520,369, dated May 22, 1894.

Application filed September 28, 1893. Serial No. 486,718. (No model.)

To all whom it may concern:

Be it known that I, JAMES JOSEPH MELVILLE, a subject of the Queen of Great Britain, residing at 6 Besswick's Road, Winnington, Northwich, in the county of Chester, in the Kingdom of England, have invented certain new and useful Improvements in Apparatus for Treating Solid, Semi-Solid, or Liquid Substances with Gases, of which the following is

10 a specification.

This invention has for its object an apparatus for treating solids or semi-solids with gases in a more convenient and thorough manner and without the handling at present

15 required.

The invention is best described by aid of the accompanying drawings, in which—

Figure 1 is a sectional elevation, and Fig. 2, a plan of the apparatus; Fig. 3, a section 20 on the center line of the annulus, showing the feed apparatus and entrance and exit pipes; and Fig. 4, a similar view showing one of the scrapers as applied above the revolving table. Fig. 5 is a detail transverse section of the rotary bed and its hood on a radial line immediately to the right of the feed hopper.

A is a rotating annular disk bed or trough; B B, a metallic or other hood, covering the same. This hood is preferably stationary and fixed and at one radius of the annulus there is a depression therein forming a hopper C having a feeding device, the material to be placed in the hopper forming a seal 35 to prevent the exit of gases. Any ordinary feeding apparatus which will spread the material evenly over the surface of the bed will do. Beyond this feed device, I insert, through the roof of the hood, the exit pipe E for the 40 gases. On the opposite side of the hopper I place the gas entrance pipe F and also a V pointed plow G, plowing the solid matter to a discharge pipe H on each side of the annular bed, except in the case where liquids are 45 treated, in which case a simple discharge pipe may be all that is required. At various radii I place baffle plates and scrapers I J, the baffle plates I being arranged to bring the gases down to and in contact with the material 50 treated, and the scrapers J to plow up and stir the same, so as to enable the gases more thoroughly to permeate it. The handles Y

can be used to actuate the scrapers or to set them at any desired angle. The junction between the hood and the rotating bed or table 55 is formed by a circular lute K which varies with the nature of the gas used. When chlorin is the gas, a solution of a chlorid such as chlorid of calcium makes a good lute. When other gases are used, oil, water or other 60 liquid or solution not combining with and not a solvent of the gases can be used instead of chlorid of calcium. To prevent the gas at its entrance from passing to the right side of the hopper, there are flanges c 65 projecting into the lute trough at both ends of the hopper C. On the bottom or preferably the side of the annular bed, I fix an annular rack L to be driven by a cog wheel or toothed wheel M or its equivalent. The circular bed is supported on a series of rollers or wheels N, on circular rails P. As it is desirable to economize space as much as possible, I prefer to arrange several of these circular beds and hoods, one over the other or 70 alternately of larger or smaller diameter and concentric but at different levels. As, in some processes where materials are treated with gases, there is a considerable amount of condensation of vapor, and in others (where 75 great heat is evolved) cooling of the hood is desirable, I prefer to make the hood arched or pointed and supplied with an annular drip channel or trough at both of its lower edges or eaves interiorly as at R and exteriorly as 80 Q, and on the top with a perforated pipe S for spraying. This arched or pointed construction of the hood gives a sloping interior as well as exterior upper portion to the hood and thus any liquid of condensation formed 85 on said interior sloping portion will run down into the interior drip channels and be carried off therefrom by any suitable discharge pipe. The discharge chutes H can deliver into barrels U, tanks for other containers, and are 90 provided with dampers or valves V operated by hand, whereby the material is from time to time discharged as it accumulates in the chutes, and by this means all handling of the material is avoided, except what may be necessary to tightly pack the material in the barrels, tanks, &c. Revolving beds can be of bare cast iron or are covered with a material not acted upon by the materials treated or 95 100

gases employed; thus, when the apparatus is used for making bleaching powder, I prefer to lag it with pitch pine or other wood tongued and grooved in place; or to cover it with 5 bricks, tiles, or slates.

W are pillars, and X girders for supporting a second apparatus above the first, but not shown.

What I claim is—

- 10 1. In an apparatus for treating solids, semi-solids or liquids with gases, an annular rotatable table for carrying the substances to be treated, an annular hood covering said table, a depression in the hood forming a hopper, a plow, an outlet pipe for the substances and an inlet pipe for the gases on one side of the hopper and an outlet pipe for the gases and a feeding device for the substances in the hopper, said inlet and outlet pipes being 15 so arranged that the gases travel in direction opposite to the direction in which the substances travel, substantially as described.
- 20 2. In an apparatus for treating substances with gases the combination of a rotatable annular table, an annular hood covering the same, a depression in the hood forming a hopper a feeding device in said hopper for feeding the substances to be treated to said table, an inlet pipe for the gases and an outlet pipe 25 for the substance treated by the gases and an outlet pipe for the gases, substantially as described.
- 30 3. In an apparatus for treating substances with gases the combination of an annular rotatable table, an annular stationary hood covering the same, lute troughs formed about the periphery of the bed of table and its inner annular edge and a flange formed on each vertical annular wall of the hood; said flanges 35 adapted to enter respectively the said troughs, substantially as described.
- 40 4. In an apparatus for treating substances with gases the combination of an annular bed and an annular hood provided with pipes for 45 the exit of the gases and the substances being treated, the one rotatable independent of the other, a plow attached to the hood and a hopper and inlet pipe for gases immediately behind the plow, substantially as described.

5. In an apparatus for treating substances with gases, the combination of an annular rotatable table, an annular stationary hood having a sloping interior and troughs passed around at the bottom of the slope whereby any liquid of condensation on the under surface of the said hood is caught by the troughs and not allowed to fall onto the table, substantially as described. 55

6. In combination with a rotatable table and a hood above the same, a water sprinkling device mounted on said hood and troughs for carrying off the water discharged therefrom, substantially as described. 60

7. In combination with a rotatable table, a thin metal sloping hood above the same, 65 water sprinkling devices delivering onto said hood and catch water channels at the bottom of said slope inside of said hood whereby the moisture within said hood is condensed and caught, substantially as described. 70

8. An apparatus for treating substances with gases having an annular chamber provided with inlet and outlet pipes for the gases and substances to be treated by said gases respectively, and with a series of baffle plates 75 whereby the gases are forced at intervals to descend onto the substances treated in order to pass below the baffle plates, substantially as described.

9. In an apparatus for treating substances with gases, the combination of a rotatable annular table provided with a circular rack, an annular hood covering the said table, a lagging of suitable material applied on the said table, operating gearing meshing with the 85 said rack, and inlet and outlet pipes for the gases and the substances being treated, so placed that said substances move in an opposite direction to that in which the gases move, substantially as described. 90

In testimony whereof I have signed my name to this specification in the presence of two subscribing witnesses.

J. J. MELVILLE.
